CLAIM

The ornamental design for a combined light and speaker housing for emergency vehicles, substantially as shown and described.

DESCRIPTION

FIG. 1 is a front perspective view of a combined light and speaker housing for emergency vehicles showing my new design;

FIG. 2 is a top plan view thereof on an enlarged scale; FIG. 3 is a front elevational view thereof on an enlarged scale;

FIG. 4 is a rear elevational view thereof on an enlarged scale;

FIG. 5 is an end elevational view thereof on an enlarged scale.

The vehicle mounting elements are shown in broken lines in FIG. 1 for illustrative purposes only.

FIG. 1

FIG. 2

FIG. 3

FIG. 4

FIG. 5
